FIG.1

FIG. 2

4→

FIG.3

FIG.4

FIG.5

FIG.6

FIG. 1 is a perspective view of a lighter embodying our new design;

FIG. 2 is a front elevational view thereof;

FIG. 3 is an elevational view taken from one side thereof;

FIG. 4 is a cross sectional view taken on line 4—4 of FIG. 2;

FIG. 5 is a fragmentary front elevational view of a modified form of the lighter shown in FIGS. 1 through 4; and

FIG. 6 is a fragmentary front elevational view of another modified form of the lighter shown in FIGS. 1 through 4.

The dominant features of our design reside in the portions illustrated in full lines, it being understood that the lighter is broken away in FIGS. 5 and 6 for convenience of illustration and the broken line showing of letters and pictures in FIGS. 1, 2, 5, and 6 are for purposes of illustration only.

We claim:

The ornamental design for a lighter substantially as shown and described.
